CLAIM

The ornamental design for a T-type wrench, as shown and described.

DESCRIPTION

FIG. 1 is a perspective view of a T-type wrench showing the new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the handle portion of the T-type wrench shown in isolation for clarity;

FIG. 10 is another perspective view thereof;

FIG. 11 is a front elevation view thereof;

FIG. 12 is a back elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The dash-dash broken lines depict portions of the T-type wrench that form no part of the claimed design. The dot-dash broken lines define the bounds of the claimed design and form no part thereof.
